(57) **CLAIM**

The ornamental design for a lens for camera, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a lens for camera showing a first embodiment of a lens for camera, the rear view being an identical image, the right side view being an identical image, and the left side view being an identical image;

FIG. 2 is a plan view thereof;

FIG. 3 is a bottom view thereof;

FIG. 4 is a perspective view from front and plan view directions thereof; and,

FIG. 5 is a perspective view from front and bottom directions thereof.

The broken lines shown in the drawings depict portions of the lens for camera that form no part of the claimed design.
